REMOTE CONTROL TRANSMITTER

Jack De Young, Spring Lake, Mich., assignor to Zenith
Radio Corporation, a corporation of Illinois

Application September 26, 1956, Serial No. 43,096

Term of patent 7 years

(Cl. D26—14)

FIG. 1

FIG. 2

FIG. 3

Figure 1 is a perspective view of a remote control transmitter showing my new design;

Figure 2 is a rear elevational view of the remote control transmitter of Figure 1; and

Figure 3 is a bottom view of the remote control transmitter of Figure 1.

The side of the remote control transmitter in the drawing is identical to the corresponding side shown in Figure 1.

The dominant features of the design reside in those portions shown by means of full lines in the drawing.

I claim:

The ornamental design for a remote control transmitter, substantially as shown and described.
